US0D1108643S

(12) **United States Design Patent** (10) **Patent No.:** **US D1,108,643 S**
(45) **Date of Patent:** **** Jan. 6, 2026**

(54) **FEEDING BOTTLE**

(71) Applicant: **Beijing Shenchuang Century Information Technology Co., Ltd.**, Beijing (CN)

(72) Inventor: **Hao Wang**, Beijing (CN)

(73) Assignee: **Beijing Shenchuang Century Information Technology Co., Ltd.**, Beijing (CN)

(**) Term: **15 Years**

(21) Appl. No.: **29/961,886**

(22) Filed: **Sep. 9, 2024**

(51) LOC (15) Cl. **07-01**

(52) U.S. Cl.

USPC **D24/197; D7/534**
